UNITED STATES PATENT OFFICE.

MILTON McCARTER, OF BOONE COUNTY, INDIANA.

WIRE-WORKING DEVICE.

1,144,217.

Specification of Letters Patent. Patented June 22, 1915.

Application filed October 1, 1914. Serial No. 864,489.

To all whom it may concern:

Be it known that I, MILTON McCARTER, a citizen of the United States, residing in the county of Boone and State of Indiana, 5 have invented a new and useful Wire-Working Device, of which the following is a specification.

The present invention appertains to a wire working device, and aims to provide a novel 10 and improved implement for use in splicing or wrapping wires in making fences, or for other purposes.

The present invention contemplates the provision of a wire working device of unique 15 construction, which is applicable to a wire in a novel manner, and which embodies means for wrapping or twisting another wire therearound in an efficient and convenient manner.

20 Another object of the invention is to provide in a wire working implement, a rotary twisting device having means for receiving a wire, and embodying means for automatically locking the wire therein when the 25 twisting or winding action is started.

It is also within the scope of the invention, to improve the implement generally in its construction, to enhance the utility thereof.

With the foregoing and other objects in 30 view which will appear as the description proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

The invention has been illustrated in its 40 preferred embodiment in the accompanying drawing, wherein—

Figure 1 is an elevation of the device, as in use. Fig. 2 is a front view of the device, portions being broken off. Fig. 3 is a sectional view taken on the line 3—3 of Fig. 2. Fig. 4 is a sectional view taken on the line 4—4 of Fig. 3.

In carrying out the present invention, there is provided a U-shaped frame or body 50 1, one arm of which is in the form of an ear 2 having a circular opening or bore 3 and an entrance slot 2^a extending from the said

opening to the free end of the arm or ear 2. The free end of the other arm of the frame or body 1, is provided with an open 55 slot 4 for receiving a wire, as will herein-after appear. The intermediate or yoke portion of the frame 1 is provided with an outstanding hub or sleeve 5, through which a shaft or spindle 6^a is journaled having a 60 squared tapered portion 6 for the engagement of a crank brace, a beveled gear 7 being keyed or otherwise secured upon the end of the shaft 6^a within the frame 1. Any suitable crank brace may be employed for 65 conveniently rotating the beveled gear 7.

Carried by the arm or ear 2 of the frame is a rotary twisting or winding member or head 8 comprising a beveled gear 9 intermeshing with the beveled gear 7 and having 70 a boss or hub 10 journaled within the opening 3 and flush with the outer face of the arm or ear 2, the gear 9 resting against the inner face of the said arm or ear 2. The rotary member or head 8 also includes a 75 collar or annular member 11 resting snugly against the outer face of the boss 10, and secured to the said boss by means of screws or other securing members 12 engaged through the collar 11 and taking into the boss 10 of 80 the beveled gear 9. The collar 11 is provided with an annular outstanding flange 13 bearing against the outer face of the arm or ear 2 to hold the beveled gear 9 in place, but to enable the said gear to rotate freely 85 without moving longitudinally.

The beveled gear 9 and its boss 10, and the collar 11 are provided with alining radial slots 14 and 15 which are adapted to register with the slot 2^a of the ear 2, and the gear 9 and its boss 10 are provided with a central opening or bore 16 alining with the opening or bore of the collar 11. A sleeve or tubular member 17 is journaled within the bores of the beveled gear 9 and collar 11 to oscillate freely therein, and is provided along one side with a slot 18 adapted to register with the slots 14 and 15 when the sleeve or tubular member 17 is rotated properly. The sleeve 17 is provided with a radial arm 19 at 100 its outer end, and working within an arcuate recess or cut away portion 20 provided in the outer face of the collar 11.

A disk or plate 21 is secured to the outer

face of the collar 11 under the heads of the securing members 12, and is provided with a central opening 22 registering with the bore of the sleeve 17, the disk or plate 21 having a radial slot 23 leading from the opening 22 and alining with the slots 14 and 15.

The disk 21 which is secured to the outer face of the collar 11 will maintain the sleeve 17 in place and the disk 21 is provided adjacent the recess or cut away portion 20 of the collar 11, with an arcuate slot 24 and the shank of a hook 25 extends through the slot 24 and is riveted or otherwise secured 15 to the arm 19 of the sleeve 17. The arm 19 working within the recess 20 and the shank of the hook 25 working within the slot 24, will enable the sleeve 17 to oscillate with respect to the bevel gear 9 and collar 11, and 20 the oscillatory movement of the said sleeve will also be limited properly. The parts are so arranged, that when the arm 19 is swung in one direction, counter clockwise as seen in Fig. 2, the slot 18 of the sleeve 17 will be 25 brought into alinement or registration with the slots 14, 15 and 23, as suggested in Fig. 4, and when the arm 19 is swung in the other direction, the slot 18 of the sleeve 17 will be brought out of registration with the said 30 slots 14, 15 and 23.

In operation, to apply the device to a wire 26, the arm 19 of the sleeve 17 is swung in the proper direction to bring the slot 18 of the sleeve in register with the slots 14, 35 15 and 23, and the shaft 6 is then rotated by a crank brace to bring the said slots in register with the slot 2^a of the ear 2. This will permit the wire 26 to be received by the said slots for causing the wire to be engaged 40 within the sleeve or tubular tumbler 17, and the wire 26 may also be simultaneously engaged by the slot 4 for holding the frame 1 against swinging movements about the axis of the shaft 6^a as a center. The numeral 27 45 designates a second wire which is spliced to the wire 26, the end 28 of the wire 27 being engaged by the hook 25 of the arm 19, to wind or wrap the end portion of the wire 27 about the wire 26, as at 29. To accomplish 50 this result, the crank brace is rotated in the proper direction, which will rotate the head 8, and the hook 25 engaging the end 28 of the wire 27, will hold the arm 19 still until the head 8 has rotated sufficiently 55 to carry the arm 19 with it.

As will be apparent, the present contrivance may be employed in various manners for wire working purposes, and is particularly adapted for wrapping or winding one 60 wire or portion about another for splicing or similar purposes. The salient or cardinal feature of the invention resides in the provision of the sleeve or wire-receiving

member 17 having a limited movement with respect to the rotary member or head 8, and 65 having means for the engagement of a wire whereby when the rotary member or head 8 is rotated, the slot of the sleeve 17 will be automatically brought out of registration with the slot of the said head for locking 70 the wire within the sleeve and head. The other advantages and attributes of the present invention will be obvious from the foregoing, taken in connection with the drawing, without further comment being deemed 75 necessary.

Having thus described the invention, what is claimed as new is:

1. In a wire working implement, a rotary member having a slot, an oscillatory wire-receiving element carried by the rotary member to oscillate freely therein and having a slot adapted to be brought into and out of registration with the aforesaid slot, one of the said parts being adapted to be 85 rotated, and the other having wire-engaging means, and means for limiting the oscillatory movement of the wire-receiving element relative to the rotary member.

2. In a wire working implement, a rotary 90 head having a slot, an oscillatory sleeve journaled within the head to oscillate freely therein and having a slot adapted to be brought into and out of registration with the aforesaid slot, the head being adapted 95 to be rotated, and the sleeve having wire-engaging means, and means for limiting the oscillatory movement of the sleeve relative to the head.

3. In a wire working implement, a rotary 100 head having a slot, an oscillatory sleeve mounted within the said head to oscillate freely therein and having a slot adapted to be brought into and out of registration with the aforesaid slot, the head being adapted to 105 be rotated, and the sleeve having an arm provided with wire-engaging means, and means for limiting the movement of said arm.

4. In a wire-working implement, a rotary 110 head having a bore and a slot leading therefrom, an oscillatory sleeve mounted within the said bore and having a slot adapted to be brought into and out of registration with the aforesaid slot, the sleeve having an arm 115 at one end, and a plate secured to the said head and over the said end of the sleeve to hold the sleeve in place, the plate having a slot, and the said arm having wire-engaging means projecting through the said slot. 120

5. In a wire working implement, a rotary member having a slot, an oscillatory wire-receiving element carried by the rotary member to oscillate freely therein and having a slot adapted to be brought into and 125 out of registration with the aforesaid slot,

a wire-engaging portion carried by the wire-receiving element, and a portion carried by the rotary member and having an arcuate slot through which said wire-engaging portion projects to limit the oscillatory movement of the wire-receiving element relative to the rotary member.

In testimony that I claim the foregoing as my own, I have hereto affixed my signature in the presence of two witnesses.

MILTON McCARTER.
